UNITED STATES PATENT OFFICE.

ERNEST M. SYMMES, OF WILMINGTON, DELAWARE, ASSIGNOR TO HERCULES POWDER COMPANY, OF WILMINGTON, DELAWARE, A CORPORATION OF DELAWARE.

AMMONIUM-NITRATE EXPLOSIVE.

Application filed November 8, 1924. Serial No. 748,549.

The object of my invention is to provide an ammonium nitrate explosive which is distinguished from ordinary ammonium nitrate explosives in that it is less hygroscopic, more sensitive, much less dense, thus allowing a higher cartridge count, and which, as it passes through the transition point at 32° C., will not "set up" (harden) and so become so relatively insensitive that it may not detonate properly.

The manufacture of my improved explosive is dependent on the use of ammonium nitrate having peculiar novel physical characteristics, and in order to properly describe the production of explosives embodying this invention, it is necessary to describe the improved ammonium nitrate which is a constituent of the explosive and the method of making it.

In the ordinary process of making ammonium nitrate, it is customary to prepare weak solutions of the salt and evaporate the solution to a certain concentration at a certain temperature, after which the solution is discharged into a graining kettle and slowly crystallized with agitation and cooling at a certain rate. The rate of crystallization and concentration of the evaporated solution controls the fineness of the product. Slow crystallization of a highly concentrated solution produces coarse particles in the form of irregular botryoidal solid crystals. Crystallizing at an increased rate results in relatively fine particles, which are also in the form of solid crystals.

Granular ammonium nitrate produced by this process is composed of solid grains, has greater density and hygroscopicity than is desirable, and when passing through the transition point at 32° C. (89.6° F.) there is considerable external expansion, which constitutes a serious objection to explosives containing ammonium nitrate in substantial proportion, as the explosive sets (hardens) as it passes through the transition point and becomes relatively insensitive and may not detonate properly.

The granular ammonium nitrate embodying the present invention is superior to the product formed by crystallizing a more or less concentrated solution in a graining kettle. As compared with the ordinary product, it is much less dense, thus allowing a higher cartridge count in ammonium nitrate

permissible explosives; it is more sensitive; 55 it is less hygroscopic; and in passing through the transition point at 32° C., there is less external expansion and it therefore does not exhibit such a marked tendency to "set up".

It is certain that some of the above qualities, and it is possible that all of them, are due, in whole or in part, to the peculiar novel physical characteristic exhibited by the granular ammonium nitrate embodying 60 the present invention: namely, the granules or particles are substantially spherical in form and have a hollow center. Such hollow spherical particles cannot be manufactured by the process in general use: namely, 65 the crystallization in graining kettles with agitation and cooling. On the other hand, their formation is not necessarily dependent on the use of any particular process and is certainly not dependent on the use of 70 any particular apparatus. In order, however, that my improved product may be produced by those skilled in the art, I shall describe a process of making it which has been found entirely satisfactory as well 75 as operative. This process is set forth in a companion application filed of even date herewith, Serial Number 748,548. It comprises the projection of an evaporated solution of ammonium nitrate, through a nozzle or atomizer, at a substantially definite 80 pressure, into a gaseous cooling medium. An apparatus adapted to carry out the process is shown in the accompanying drawing, which is a longitudinal sectional view of 85 such apparatus.

A weak neutral ammonium nitrate liquor is concentrated in the evaporator *a*. From the evaporator the more or less concentrated solution, by means of a pump *b*, is conveyed 90 through a steam-jacketed pipe *c* and discharged through a nozzle *d* into the spray chamber *e* under sufficient pressure to effect the atomization of the solution. It should be understood that the term "atomization" 95 is used in its popular sense to imply a division of the solution into a number of very fine particles, which will solidify before they have traversed the height of the spray chamber. The spray chamber is of substantial 100 dimensions and is provided with a sloping bottom communicating with a hopper *f* which discharges the material into a ro-

tating drying cylinder *g*. From the drying cylinder the dried material is discharged, say, onto a screen *h*; the grains which it is desired to utilize as an explosive ingredient 5 passing through the screen into a receiver *i*, while the tailings pass over into a separate receiver *j*. By means of a heater *k* and a blower *m*, a current of hot air or other gas is forced through the drier, the air thence 10 escaping through the hopper *f* into the spray chamber *e*.

The character of the material produced by the improved process is controlled by the 15 conditions under which the process is carried out. It has been found that the density of the material varies in a substantially direct ratio to the freezing point of the solution sprayed and in a substantially inverse ratio to the temperature of the solution and 20 degree of atomization. In other words, the density of the product resulting from spraying a solution having a freezing point only slightly below the temperature of the solution when sprayed will be higher than that 25 of the product from a solution having the same freezing point but sprayed at a higher temperature. By controlling the freezing point and temperature of the solution and the degree of atomization, the character of 30 the product may be controlled. The freezing point of the solution varies with the degree of concentration. The degree of atomization may be varied by varying the pressure at the nozzle and to some extent by 35 varying the temperature of the solution when sprayed.

As an illustration of the process, a weak 40 solution of ammonium nitrate is concentrated in the evaporator *a* to a point where the solution has a temperature of 310° F. and at which the ammonium nitrate if taken out would freeze or crystallize at 280° F. With a steam pressure of fifty pounds to the 45 square inch on the jacketed feed pipe *c*, the solution is delivered through the pump to the nozzle *d* at a pressure of twenty pounds to the square inch.

The heated air in chamber *f* may be at any 50 desired temperature (say 100° F. to 150° F.) and is substantially devoid of moisture. This air, however, is very cold relatively to the incoming spray of ammonium nitrate, and almost immediately cools the sprayed particles to the point of solidification. It 55 will be understood that there is a continuous current of dry air flowing into the bottom of chamber *e* and out the ventilators *o* at the top thereof.

The ammonium nitrate is projected in the 60 form of a vast number of particles of spherical form. From contact with the cooling gaseous medium filling the spray chamber, these spheres quickly form an exterior solidified shell. The interior of each particle 65 freezes more slowly and, due to the contrac-

tion that takes place on cooling, a void space is left in the interior. The product has an apparent density of about .70 and a fineness (with the freezing point, temperature and degree of atomization specified as an example) such that ninety-five per cent will pass 70 through a ten mesh screen and be held on a forty mesh screen. By increasing the atomizing action, finer particles are produced. For example, the degree of fineness may be 75 such that not more than five per cent will be held on a forty mesh screen, while five per cent or more will pass through a hundred mesh screen. Whatever the degree of fineness, the grains have a spherical form 80 with an interior void space. Besides being much less dense than granular ammonium nitrate produced by the ordinary method, they are less hygroscopic and show less increase in volume when passing through the 85 32° C. transition point.

The size and density of the material are both affected by, and may be controlled by 90 regulating, the freezing point, temperature and degree of atomization of the liquid when sprayed. In all cases, however, the density will be low as compared with the ordinary product and there will be a close approximation to uniformity in size. The density 95 can be easily varied from .6 to .9.

While the weak solution is described as 100 being concentrated to a point where the solution has a temperature of 310° F., crystallizing at 280° F., it is contemplated that these temperatures shall be subject to variation, dependent on the character or quality 105 that it is desired to impart to the ultimate product. It is impracticable, however, to carry either the crystallizing temperature or the evaporating temperature much higher than 310° F., as decomposition occurs in the neighborhood of 320° F. The lowest practicable crystallizing temperature would be 250° F. or higher. The temperature of the gas entering the spray chamber is immaterial so long as it is substantially below the 110 temperature of the liquid as it is being atomized. The gas should, of course, be nearly free from moisture. All required conditions can be satisfied by using air as the gaseous 115 cooling medium and heating it to above 100° F. and below 150° F.

The following are examples of ammonia 120 permissible explosives embodying my invention, bearing in mind that the ammonium nitrate ingredient has the peculiar characteristics and qualities hereinbefore described.

An ammonia permissible explosive having the following typical composition:

	Per cent.	125
Nitroglycerin, nitropolyglycerin, nitro-sugar, nitroglycol, or any other similar liquid explosive	10	
Carbonaceous material	10	
Ammonium nitrate	80	130

Ammonia dynamite (the example given being a low freezing dynamite of so-called 40% strength):

	Per cent.
5 Any of the above specified liquid explosives	17
Nitroaromatic compounds	3
Sodium nitrate	41
10 Carbonaceous material	11
Ammonium nitrate	28

Ammonia gelatin (the example given being low freezing):

	Per cent.
15 Any of the above specified liquid explosives	29
Nitrocotton	0.6
Sodium nitrate	46.4
20 Sulphur	3.0
Carbonaceous material	15.0
Ammonium nitrate	6.0

Having now fully described my inven-

tion, what I claim and desire to protect by 25 Letters Patent is:

1. An explosive composition comprising a liquid explosive, carbonaceous material and ammonium nitrate in the form of a multitude of substantially spherical grains with 30 internal cavities.

2. An explosive composition comprising a liquid explosive, carbonaceous material and ammonium nitrate in the form of hollow granules having a density between .6 and .9. 35

3. An explosive composition comprising a liquid explosive, carbonaceous material and ammonium nitrate in the form of granules having an internal void space and having, as compared with ordinary commercial ammonium nitrate, substantially lower density 40 and less hygroscopicity and which will not substantially set or harden in passing through the transition point at 32° C.

In testimony of which invention, I have 45 hereunto set my hand, at Wilmington, Del., on this 5th day of November, 1924.

ERNEST M. SYMMES.
